APPARATUS FOR EXTRACTING LIQUID HYDROCARBONS FROM OIL SHALE

Filed Nov. 23, 1926

Fig.1.

UNITED STATES PATENT OFFICE.

AUGUST SCHILLING, OF SAN FRANCISCO, RICHARD SACHSE AND DIMITRI LIAMIN, OF LOS ANGELES, AND THEOFIEL CALLAERT, OF SAN FRANCISCO, CALIFORNIA.

APPARATUS FOR EXTRACTING LIQUID HYDROCARBONS FROM OIL SHALE.

Application filed November 23, 1928. Serial No. 150,204.

The oil shale of California differs physically and chemically from the oil shales of other parts of the United States, the beds occur in massive formation, are soft, of a 5 brown or brownish-yellow color, and when freshly broken have a strong, petroleum odor.

An analysis of this shale discloses the same to be a physical mixture of three parts, namely:—oil not chemically combined with 10 the substance of the shale and which can be easily extracted by solvents or by heat; organic matter in which carbon is chemically combined with different materials; and the inert mineral matter which would remain in 15 the form of ashes from combustion.

The present invention relates to an apparatus for the extraction by heat of oil from such California shale, and the production of gas during such oil extraction.

20 The principal object of the invention is the extraction of oil from shale by heat, and the gasification, with the aid of steam and air, of the carbonaceous and volatile substances contained in the shale producing the com- 25 monly termed 'blue gas.'

A further object is the condensing of the gases of combustion so produced from the shale to separate the water gas from the oil, and the recovering of the oil extracted by 30 the heat of combustion and by the condensing of the products of combustion.

The objects of the present apparatus are to provide an organized structure, affording means in which the shale may be ignited and burned downwardly with the combustion gases passing downwardly therethrough in the presence of steam for the extraction of the oil therein and the production of oil and gas containing gases of combustion.

40 A further object of the invention is to provide in connection with the organized apparatus, cooperating units whereby the gas containing products of combustion resulting from the ignition of the shale is employed in 45 its condensing affording steam to assist in the combustion of the shale.

With the above and other objects in view, the invention consists broadly in the produc-

tion of water and oil gas and oil from shale by what may be termed a down draft combustion process.

In the drawings disclosing the preferred embodiment of apparatus for carrying out the present invention—

Fig. 1 is a vertical sectional view of the 55 generator within which the shale is deposited and burned.

Fig. 2 is a vertical sectional view of one of the steam generators.

Fig. 3 is a view in perspective of a portion 60 of the grate forming the bottom generator within which the shale is burned.

In the drawings, wherein like characters of reference designate corresponding parts—1 indicates the shell of a water gas generator 65 having a refractory lining 2 and an insulating layer 3 lying between the same. A charging opening 4 is provided in the upper end of the generator and through which the shale, in relatively small pieces, is fed in charging 70 the generator. A flange 5 surrounds the opening 4 and disposed annularly thereon in spaced relation thereto is a wall 6 connected at its lower end with the base of the flange by a wall 7, the parts forming an open topped 75 liquid seal chamber 8 for containing a sealing fluid, not shown.

A closure member 9 is adapted to snugly fit within the opening 4 to preclude the escape of the combustion gases therefrom, the same 80 being suspended from the upper wall 10 of a cap which is in turn provided with an annular flange for reception within the chamber 8. Any suitable mechanism may be employed 85 for removing and replacing the member 9, that illustrated consisting of a davit 11 carrying sheaves 12 over which operates a flexible member 13' attached to the member 9.

The base of the generator is open at 13 and 90 the shell 1 is illustrated as depending below said opening, it being received within the liquid seal box 14 of a generator bottom 15 mounted on arms 16 secured to a vertically reciprocable shaft 17 which is in turn axially 95 rotatable in guide bearings 18 carried by the

supporting frame members 19. The bottom 15 is raised and lowered to and from the bottom of the generator by a lever 20 pivoted at 21 and carrying a collar 22 loosely surrounding the shaft 17, and connected with the lever by links 23. The collar 22 bears against the underside of flange ring 24 held to shaft 17. The bottom 15 is provided with a conical oil collecting depression 25 and from the same 10 extends a trapped pipe 26 leading to the flanged mouth of a conveying pipe 27.

A grate A is provided within the generator, the same consisting of leaf sections 28 and 29 connected by a shaft 30 extending diametrically across the generator with one end projecting through the generator wall. The shaft 30 is keyed to the hubs of leaf section 28 and affords a pivot about which the hubs 31 of section 29 swing, the latter hubs having 20 aligned bores through which the shaft extends, and the hub ends at opposite sides of the section being fulcrumed in the generator wall affording a fulcrum for the grate. One end of the shaft 30 and the corresponding 25 end of the hub 31 of section 29 are polygonally fashioned as at 32 to receive suitable tools employed in raising the leaf sections to a horizontal position after they have been released to drop and dump the contents therefrom. 30 When raised to a horizontal position, the free ends of sections 28 and 29 rest on releasable spring pressed supports 33 reciprocable in openings in the generator wall.

An annular duct 34 having wall openings 35 for the admission of the gases of combustion of the ignited shale body, lies within the base of the generator above the grate A with an outlet duct 36 leading therefrom and extending through the generator wall.

40 Air for combustion and steam to assist in the extraction of the oil from the shale and to assist in the formation of the so-called blue gas to pass downwardly through the body of shale, is admitted into the upper part of the generator by the respective coils 4' and 4'', the former connecting with a supply pipe 5', valve controlled at 6', and the latter connecting with a pipe 7' which is in turn connected to the steam generator 40.

50 A charge of shale deposited within the generator through the opening 4 is ignited at its top and burns downwardly within the generator, the gases of combustion being drawn off through duct 36, and the oil released from the shale and not consumed in combustion collecting in the bottom 15, passing therefrom through the trap pipe 26. After any given charge of shale has been consumed by combustion, the bottom 15 of the 60 generator is lowered by operation of handle 20, and after being lowered the bottom is swung laterally on its shaft 17 from beneath the open bottom of the generator. The supports 33 are then withdrawn enabling the 65 sections 28 and 29 to drop, dumping the ash

heretofore supported by the grate through the chute 37, Fig. 1. The oil extracted by the heat of combustion delivered to pipe 27 passes therethrough to any suitable apparatus for further treatment. The pipe 36 for conveying the gases of combustion containing the carbonaceous and volatile matters removed from the shale passes through a heater 40, the outlet of which is connected with a suction means, not illustrated, which means creates a down draft in the generator 1.

The heater 40 through which pipe 36 conducts the gases generated by the combustion of the shale in generator 1, is illustrated in Fig. 2. It consists of a shell 65 closed by end plates 66, the upper being provided with a steam outlet 67 and the lower with a water inlet 68. Transverse division walls 69 and 69' separate the interior of the shell into gas chambers 70 and water chambers 71. Through the former is conveyed gases of combustion from the respective generators. Water tubes 72 extend from chamber 71 through chamber 70 and connect with the steam chamber 73 in the upper end of the shell, and said tubes convey streams of water for absorbing heat from the gases in chamber 70, cooling the gases and converting the water into steam. Water enters the chamber 71 through fitting 76 to which water feed or inlet pipe 68 is connected. The passage of water through outlets 75 is controlled by a normally seated needle valve, not shown, unseated by the action of a rod 80 extending through one of the tubes 72 and carrying on its upper end a float 81 in steam chamber 73.

A thermostat 82 of any well known construction is connected with and operates the valve 6' to admit more or less air through the coil 4', in accordance with the temperature of the gases passing through pipe 36.

The apparatus illustrated for reducing the shale is of the type wherein successive batches of material are treated; it is to be understood, however, that under feed and automatic stoking devices may be utilized in connection therewith to render this generator semi-automatic.

We claim:

An apparatus for extracting liquid hydrocarbons from oil shale, comprising a refractory lined tubular generator provided at its upper end with a charging opening through which shale to be burned is delivered into the generator and at its lower end provided with an ash removing opening, a fluid sealed removable closure for the upper opening, a fluid sealed removable closure for the lower opening, said latter closure providing means for collecting the liquid hydrocarbon released from the shale and passing downwardly therethrough, means for raising and lowering the latter closure relative to the lower opening and for swinging the same laterally from beneath the generator, a grate

within the generator for supporting the shale therein, means surrounding the generator upper opening through which oxygen for combustion is supplied to the generator above

the level of the shale body, and means surrounding the generator immediately above the grate and through which the products of combustion and gases of generation of the

shale are withdrawn from within the generator creating a down draft therein.

In testimony whereof we have signed our names to this specification.
